COLOSTOMY DEVICES

Amicare De Camillis, Vancouver, British Columbia,
Canada

Application January 31, 1955, Serial No. 485,140

6 Claims. (Cl. 128—283)

My invention relates to improvements in colostomy devices.

This invention relates to an apparatus such as is worn by a person who has undergone a colostomy, wherein a permanent opening is formed in the abdominal wall to communicate with the colon and through which excrement is extruded by the normal digestive process. Such an apparatus normally includes a receptacle of some form which is supported over the abdominal opening to receive matter being discharged therefrom.

The objects of the present invention are to provide a device of this nature which may be worn with comfort; to provide means whereby an effective seal is formed between the device and the body of the wearer, and to provide a material receiving bag which may be removed and disposed of without fear of soiling the clothing of the wearer. These and other objects will appear as the specification proceeds.

Referring to the accompanying drawings:

Figure 1 is a front elevational view of the invention.

Figure 2 is an enlarged sectional view taken on the line 2—2 of Figure 1.

Figure 3 is a sectional detail view showing the normal shape of the pad and the sealing washer before the device is secured to the body.

In the drawings like characters of reference indicate corresponding parts in each figure.

The numeral 1 indicates generally a support member consisting of an annular plate 2 having a central opening 3. Above the opening the plate is provided with a forwardly projecting flange or hood 4, the purpose of which will hereinafter appear. Extending from the sides of the plate are substantially U-shaped loops 6 and the device is provided with a waist encircling adjustable band 8 fitted with hooks 9 which engage said loops.

Secured to the rear face of the plate 2 is a pad 10 of foam rubber or similar soft resilient material and having a central opening 11 in alignment with the opening 3 of said plate. The pad is rectangular in cross section, see particularly Figure 3, and is adapted to be engaged and deformed on its rear face by a washer 14 of rubber or the like. The washer is provided with a vertical flange 15 and a forwardly projecting horizontal flange 16 and the intersection of the two flanges is thickened and rounded as at 17.

The device is provided with an outer supporting sack 20, preferably of plastic, which is fitted at its upper edge with front and rear elastic bands 21. Each of the bands 21 is fitted with small hooks 23 which are adapted to be connected to the loops 6 so that the sack may be suspended from the plate 2 with the mouth of the sack somewhat constricted, as shown in Figure 2. The sack is adapted to enclose a disposable bag 25, also preferably of plastic or similar material, which bag is of sufficient length to project some distance above the supporting sack.

The device is prepared for use by placing a bag within the sack and threading the upper edge of said bag through the openings 3 and 11. The rim 26 of the bag is then folded into contact with the outer periphery of the pad 10, see Figure 2. The washer 14 is fitted in position by entering its flange 16 into the opening 11 of the pad so that the bag is securely gripped therebetween.

In Figure 2 the abdominal wall is shown in dotted line at 30 with the opening being indicated by the numeral 31. The member 1 is placed against the wall as shown

2

and the band 8 is passed around the waist and secured to the loops 6. By adjusting the band 8, the member 1 is supported against the wall 30 with sufficient pressure to slightly indent said wall and to distort the washer 14 to the extent that a seal is formed between the washer and the wall. The thickened portion 17 of the washer serves to compress the inner corner of the pad 10 as shown at X in Figure 2, so that no possibility exists of fecal matter finding its way past the bag and the adjoining surface of the washer. As matter is extruded into the bag its flow is not obstructed by the wearer's clothing pressing against the device since the hood 4 supports said clothing beyond the plane of the plate 2. When it becomes necessary to dispose of the bag 25 it is a simple task to remove the bag and replace it with another as above described.

The thickened and rounded portion 17 of the washer 14 and the resilient thrust of the inner corner of the pad causes a greater inward pressure to be applied to the body wall 30 at the periphery of the abdominal opening than elsewhere, thereby making it possible to form a perfect seal between the washer 14 and the skin without unduly tightening the waist band 8.

What I claim as my invention is:

- 25 1. A colostomy device comprising an annular member adapted to be supported over the opening in the abdominal wall, said member having a resilient annular pad secured to its rear face, a washer coacting with said pad to form a seal, a bag, the open end of said bag being inserted through the opening of the resilient pad, said bag being gripped in open position between said pad and the washer when the device is pressed against the wearer's body.
- 30 2. A colostomy device comprising an annular member adapted to be supported over the opening in the abdominal wall, said member having a resilient annular pad secured to its rear face, a washer interposed between said pad and the abdominal wall, said washer having a thickened portion adjacent its inner periphery adapted to form a seal, a bag, the open end of said bag being inserted through the opening of the resilient pad, said bag being gripped in open position between said pad and the washer when the device is pressed against the wearer's body.
- 35 3. A colostomy device comprising an annular member adapted to be supported over the opening in the abdominal wall, said member having a resilient annular pad secured to its rear face, said pad having inner and outer corners, a washer interposed between said pad and the abdominal wall, said washer having a thickened portion adjacent its inner periphery forming a seal, a bag, the open end of said bag being inserted through the opening of the resilient pad, said bag being gripped in open position between said pad and the washer when the device is pressed against the wearer's body.
- 40 4. A colostomy device as claimed in claim 3 and a sack suspended from the member to support the free end of the bag.
- 45 5. A colostomy device as claimed in claim 3 wherein the annular pad is rectangular in cross section.
- 50 6. A colostomy device as claimed in claim 1 wherein the annular member is provided on its outer face with a hood projecting therefrom and extending around the upper part of the annulus.
